UNITED STATES PATENT OFFICE.

JONATHAN PRESCOTT GROSVENOR, OF WORCESTER, MASSACHUSETTS.

DESIGN FOR A BOOT.

42,322.

Specification for Design.

Patented Mar. 19, 1912.

Application filed August 10, 1910. Serial No. 576,608. Term of patent 14 years.

To all whom it may concern:

Be it known that I, JONATHAN PRESCOTT GROSVENOR, a citizen of the United States, residing at Worcester, in the county of Worcester and Commonwealth of Massachusetts, have invented a new, original, and ornamental Design for a Boot, of which the following is a specification, reference being had to the accompanying drawing, forming part thereof.

The figure is a perspective view of a boot, showing my new design.

I claim:

The ornamental design for a boot, as shown.

JONATHAN PRESCOTT GROSVENOR.

Witnesses:

CARL M. BLAIR,
A. I. BIGELOW.
